Primary Examiner — Paula Allen Greene(57) **CLAIM**

The ornamental design for a microphone isolation shield, as shown and described.

DESCRIPTION

FIG. 1 is a first perspective view of a microphone isolation shield showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the microphone isolation shield thereof;

FIG. 10 is an enlarged view of the selected portion 10 in FIG. 1; and,

FIG. 11 is an enlarged view of the selected portion 11 in FIG. 2.

The dot dash broken lines encircling portions of the microphone isolation shield in FIGS. 1 and 2 and illustrated in the enlarged views of FIGS. 10 and 11 form no part of the claimed design.
